UNITED STATES PATENT OFFICE

RAY D. STEVENS, OF SAN BERNARDINO, CALIFORNIA.

INTERNAL-COMBUSTION ENGINE.

1,137,296.

Specification of Letters Patent. Patented Apr. 27, 1915.

Application filed October 28, 1912. Serial No. 728,273.

To all whom it may concern:

Be it known that I, RAY D. STEVENS, a citizen of the United States, residing at San Bernardino, in the county of San Bernardino and State of California, have invented new and useful Improvements in Internal-Combustion Engines, of which the following is a specification.

This invention relates to internal combustion engines of the four-cycle type in which a combustible mixture formed outside the engine is introduced into the cylinder during the suction stroke of the piston and in which the burnt gases are driven from the cylinders after combustion by the return of the pistons.

My invention relates particularly to the devices that control the admission of the fresh gases and the escape of burned gases. In engines of this type, as heretofore constructed, lift or puppet valves operated either by the pressure of the gases or of the atmosphere, or by suitable cam mechanism have generally been employed and experience shows that the use of such valves is open to many objections.

The general object of my invention is to provide for admission and exhaust of the gases by means which shall obviate the objections above referred to, and this result is attained by using reciprocating piston valves having rings on their ends. These rings prevent leakage of gases, assist in the lubrication, and wipe out carbon and other foreign matter from the valve seat and so prevent it from unseating the valve. The rings also cause the valve chamber to wear even, and expand as the chamber becomes worn, thus preventing leakage.

One specific object of my invention is to secure self-lubrication of the valves, the same being surrounded with a water-jacketed valve chamber in which said valves operate easily and coolly.

Another specific object of my invention is to secure the automatic removal of dirt, carbon and grease from the valve seat and to convey the same to some exterior point where the same may be conveniently discharged.

Another specific object of my invention is to secure a considerable reduction in the gas friction as the mixture passes through the valve ports, the same permitting a freer

rush of said mixture into and out of the combustion chamber during the admission and exhaust strokes. This feature operates to increase the useful power of my engine by reducing lost work of admission and exhaust, and obviously secures the advantage of an increased over all engine efficiency.

Another specific object of my invention is to secure a positive return of the valves, thereby obviating the uncertainty of operation attendant upon spring or other non-positive returning means.

Another specific feature of my invention is that I secure rapid valve motion during the half cycle in which the valves are active and secure a valve dwell or rest during the half cycle in which the valves are inactive. This feature permits the use of a comparatively short valve and valve seat and reduces wear on the same.

The accompanying drawings illustrate the invention.

Figures 1, 2 and 3 are diagrammatic views in axial section through an engine embodying my invention, and showing the position of the valve operating gear at critical points of the cycle. Fig. 4 is an enlarged plan section of the engine taken on line x^4 , Fig. 5, the dust guards surrounding the valve casings being omitted in the interest of clearness. Fig. 5 is a vertical axial section through the engine showing the details and relative position of the valve operating gear, piston and the cylinder. Section is taken on line x^5 , Figs. 4 and 6. Fig. 6 is a sectional elevation along line x^6 of Figs. 4 and 5, showing my improved valves. Fig. 7 is a plan section on line x^7-x^8 , Fig. 5, and shows the square bushing and square rod for carrying the roller follower.

1 is an ordinary four cycle gas engine cylinder provided with piston 2, water jacket 3, and spark plug 4.

At diagonally opposite points, and built integral with the cylinder, are the valve chambers 5 and 6, having the transverse inlet port 7 and exhaust port 8 respectively. Through these valve chambers pass the cylindrical apertures 9 and 10 serving as seats for valves as later described, the said apertures or seats being closed at their upper ends by walls 11 and 12. Through these walls pass oil ports 13 and 14, connected

with a suitable oil supply not shown and also breathing apertures 15 and 16 permitting the admission and discharge of air from the upper portion of the chambers during normal operation of the valves 17 and 18.

Each of the valve chambers is provided with a novel cylindrical piston valve as shown at 17 and 18, similarly constructed, and having the packing rings 19 and 20 to form a gas tight joint between the valve and its seat. These rings are resilient and will automatically adjust themselves to take up any wear of the cylindrical seats 9 and 10. Valves 17 and 18 are each provided with a funnel shaped inwardly expanding port 21 bounded above by the upwardly and inwardly extending wall 22, on the side by the inwardly diverging walls 23, and on the bottom by the horizontal wall 24. As the controlling edge 25 of port 21 is raised, uncovering the lower outer edge 26 of port 7, an expanded passage through the valve is provided, permitting gas to rush freely into the cylinder. Due to the expanded shape of said valve port the gas will be subject to minimum friction or resistance during its passage through the same. On the admission stroke this reduction of gas friction reduces the back pressure on the piston face and thereby the lost or pumping work of admission. During the exhaust stroke the similar easier exit of burnt gases through the exhaust port, likewise reduces the back pressure on the piston face and thereby the lost work of exhaust. By these reductions of lost work my valve obviously secures the important advantage of raising the useful work efficiency of the entire engine.

Above the inclined wall 22, the valves are hollowed out forming the cup shaped reservoirs 27 providing the main elements of the splash lubricating system for the valves.

The lubricating oil, entering the valve chambers by ports 13 and 14, fills the reservoirs 27, and as the valve oscillates during operation, the oil is thrown out covering the upper portion of the valve seat. The oil will flow down along the seat to the rings 19 and 20 making a more perfect seal between the rings and seat, and also reducing the sliding friction between the same. Under the influence of the exploded or compressed gases the valves are pressed most forcibly against the outer portion of the valve seat tending to cause the greatest friction and wear there, and in order to supply a proportionately greater amount of lubricant to this side, notch 28 is cut into the upper edge of reservoir 27 at its outer point. Through this notch an additional amount of lubricant over and above the normal quantity provided by the splash system will feed to the outer surface of the valve and counteract the increased wearing tendency. The

valve chambers are also built with a water jacket 29 surrounding both the vertical valve seat and the horizontal ports 7 and 8. By this provision the valve is kept cool and its lubrication more readily effected, and at the same time the gases passing through the ports are kept cool and therefore condensed, securing the passage of maximum weight of gas with minimum expenditure of power.

A downwardly and outwardly inclined dirt groove 30 is cut into valves 17 and 18, the former being shown in its lowest position in Fig. 5. From this figure it is seen that the inner extremity of the dirt groove is never uncovered to the cylinder side of ports 7 or 8, but that the lower outer extremity of the groove is opened to the outer side of ports 7 or 8 when the valve has reached the lowest point in its travel. The edges of this groove will scrape the dirt, carbon and other foreign matter off the valve seat into the groove, such dirt passing down the inclined groove falling onto the ledges 31 and 32 of the ports 7 and 8 respectively. If permitted to remain on ledge 31 of the inlet port, the inrushing gases would draw the grit into the engine cylinder where damage might be done by cutting the cylinder bore. The ledge 31 is therefore inclined and the grit will run down and off the same into the adjacent receptacle 33 provided in the inlet pipe 34. The receptacle 33 is provided with a detachable portion 35 from which the grit may be discharged at suitable intervals. No such provision need be made at the exhaust ledge 32 the grit being carried away from the engine by the exhaust gases issuing through the valve port.

Each of the valves are connected through pins 36 to the rods 37 carrying at their lower ends the cam follower 38 operating in conjunction with positive return cams described below, to move the valves in correct time relation with respect to the position of the power piston 2.

The piston 2 carries the connecting rod 39, cooperating with crank 40 and power shaft 41 in the usual manner. The gear 42 on the power shaft, meshes with pinions 43 carried by the lay shafts 44. The pinions 43 are of the same diameter, and double that of gear 42, this ratio causing each pinion to make one revolution during four strokes or one cycle of the engine, the gear having made two revolutions in the same time. Mounted on the lay shafts 44 and revolving with the pinions are the rapidly acting positive return cams 45 seen best in Fig. 6, these cams being formed with the grooves 46 in which run the followers 38 imparting the cam motion to valves 17 and 18.

In Fig. 5 the piston is shown at its mid point during the exhaust stroke, and it is seen that the follower 38 of the admission valve is at the end of a dwell or rest period

determined by the dwell lobe extending from point 47 to point 48 on the semi-circular portion 49 of the cam groove and lasting from the mid-compression to the mid-exhaust points of the cycle. During this dwell there has been no function for the admission valve to perform and it has been allowed to rest motionless, causing no unnecessary wear either upon the valve or its seat. From the mid-suction to the mid-explosion point of the cycle the exhaust valve indulges in a similar dwell.

From point 47, the follower 38 and inlet valve 17 are raised rapidly by the cam, the controlling edge 25 of the valve opening the port when the follower lies under line *ab* of the admission cam, and closing it when the follower lies under line *ac*, shown best in Fig. 5. The lines *ab* and *ac* are located approximately 45° to the major cam diameter *ad*. The exhaust cam and valve operate in a manner identical with that of the inlet mechanism, except in point of time, the exhaust cam leading the inlet cam by 90° on the lay shafts. By use of my valve operating gear the life of the valves is prolonged, all unnecessary wear being avoided, and during the operating portion of its stroke the motion of the valve is accomplished with despatch, securing an effective opening of both ports for the admission and exhaust of the gases.

From the foregoing it is seen that the cylindrical valve chambers 9, 10 cut through the ports 7, 8 so as to divide said ports into axially aligned inner and outer bores that are rectangular in cross section and that the cylindrical valves 17, 18 reciprocating in said valve chambers are provided with transverse ports therethrough and that each of said valve ports has an oblique upper wall designed to extend downward and outward between said bores from the upper side of the inner bore to the lower side of the outer bore when the valve is closed. This construction is of advantage to secure maximum thrust of the compressed gases in the cylinder against the valve so as to produce maximum tightness of the valve against leakage and, furthermore, is very important for reducing impediment of the flow of gases to and from the cylinder since the valve ports 21, 22 are always fully opened to the inner bores of the ports 7, 8 even when the valves are closed, so that in reality the only obstruction to the flow of gases is the outer walls of the valves.

In Figs. 5 and 6 are shown dust guards or protecting hoods 50, suitably attached to the cylinder by means of studs 51 and wing nuts 52, the guards surrounding the valves and operating rods to prevent dust from accumulating and interfering with the operation of the same. To expose the rods 37 and the lower valve portions for repair or ad-

justment, the guards 50 may be rapidly removed by merely unscrewing the wing nuts 52.

The engine works according to the well-known four cycle principle, and from the foregoing it is thought the operation of the elements embodying my invention will be readily understood.

I claim:

1. The combination with an engine cylinder having a port, of a cylindrical valve chamber cutting through the port and dividing said port into inner and outer bores, and a cylindrical valve reciprocating in said valve chamber and provided with a transverse port therethrough, said valve port having an oblique upper wall designed to extend downward and outward between said bores from the upper side of the inner bore to the lower side of the outer bore when the valve is closed.

2. Inlet valve mechanism for gas engines, said mechanism comprising a cylindrical valve chamber, a cylindrical piston valve adapted to operate in said chamber, said valve chamber having one port communicating with the engine and another port leading into said valve chamber, the lower portion of the last said port being inclined downwardly, outwardly and away from said valve chamber, the cylindrical face of said piston valve having a downwardly and outwardly extending dirt groove cut therein, said dirt groove being adapted to open into the last said port and to deliver dirt thereto, and a removable receptacle mounted adjacent the lower portion of the last said port, said receptacle being adapted to collect the dirt deposited by said dirt groove.

3. A valve mechanism for gas engines comprising a cylindrical member to form a valve chamber, a cylindrical piston valve adapted to operate in said cylindrical member, a port communicating with the engine being formed in one side of said cylindrical member, and a second port being formed in the other side of the cylindrical member, there being a transverse port in said piston valve adapted to register with the ports through the cylindrical member, and a groove cut in the cylindrical face of said piston; said groove extending downwardly and outwardly and being adapted to open into said second port and to deliver carbon deposit thereto.

4. A valve for gas engines comprising a valve chamber, a cover for said valve chamber, an inlet pipe secured to said cover and affording communication into said valve chamber, a cylindrical piston valve adapted to operate in said chamber, said piston valve being formed with an upwardly opening cup-shaped portion adapted to form a reservoir for lubricating oil which may be supplied thereto through said inlet pipe, said

cylindrical piston valve having an aperture through that part of its side which is removed from the piston cylinder, said aperture being adapted to feed lubricating oil from said cup-shaped reservoir on the valve to the walls of the valve chamber which are removed from the engine cylinder.

In testimony whereof, I have hereunto set my hand at San Bernardino, California, this seventh day of October, 1912.

RAY D. STEVENS.
